CLOCKFACE

Richard A. Strong and Rosa M. Strong, both of 6816
Longford Drive, Dayton, Ohio 45424

Original design application Nov. 5, 1970, Ser. No. 25,841,
now Patent No. 224,033, dated June 27, 1972. Divided
and this application Feb. 22, 1972, Ser. No. 228,484

Term of patent 14 years

Int. Cl. D10—07

U.S. Cl. D10—126

FIG. 1

FIG. 2

FIG. 1 is a plan view of a clockface, showing our new design, and

FIG. 2 is a plan view of a modified form of our new FIG. 1 design.

The clockface is conventionally of no appreciable thickness.

This application is a divisional of Ser. No. D. 25,841, filed Nov. 5, 1970, and now Pat. No. D. 224,033, June 27, 1972.

We claim:

The ornamental design for a clockface, as shown and described.
